(57) **CLAIM**

The ornamental design for a table top implant tracking device, as shown and described.

DESCRIPTION

FIG. 1 is a perspective view of a table top implant tracking device showing my new design;

FIG. 2 is a front elevation view thereof;

FIG. 3 is a top plan view thereof;

FIG. 4 is a left elevation view thereof;

FIG. 5 is a right elevation view thereof; and,

FIG. 6 is a bottom plan view thereof.

The broken lines are included for the purpose of illustrating portions of the table top implant tracking device that form no part of the claimed design.

1 Claim, 3 Drawing Sheets

FIG. 3

FIG. 4
